United States Patent Office

Des. 210,669
Patented Apr. 2, 1968

210,669

VASE

Orville C. Hamon, Cedars Village, Okla.
(P.O. Box 152, Fort Smith, Ark. 72901)

Original design application Aug. 30, 1965, Ser. No. 86,757, now Patent No. 206,445, dated Dec. 13, 1966. Divided and this application Nov. 10, 1966, Ser. No. 6,139

Term of patent 14 years

(Cl. D29—28)

This is a division of application Ser. No. D. 86,757, filed Aug. 30, 1965 and now Patent No. D. 206,445, granted Dec. 13, 1966.

I claim:

The ornamental design for a vase, substantially as shown and described.
